5 Claims. (Cl. 313—318)

This invention relates to electric incandescent lamps. Heretofore incandescent lamps have generally comprised a filament assembly sealed into one end of an evacuated, or gas-filled glass bulb, the seal being covered with a protective cap which serves to support the lamp in a holder and by which the electrical connections to the filament are made.

However, incandescent lamps known as "architectural" and "festoon" lamps comprise a tubular glass envelope having a filament extending axially therein, the electrical connections to the filament passing through seals located at the ends of the envelope.

In accordance with the present invention, an electric incandescent lamp has a sealed envelope comprising two preformed members of generally rectangular configuration and of light transmitting vitreous material sealed together along their adjacent flanged peripheries with at least one filament supported within the envelope with each electrical connection thereto extending in sealed relation through opposed edges of the joint between the members to the exterior of the envelope.

The two pre-formed members are so shaped that when they are sealed together the resulting envelope is in the form of a hollow panel which is suitable for mounting directly on either a wall or ceiling. Each member may be in the form of a trough provided at its mouth with an outwardly turned flat rim, and in order to form the envelope the members are assembled in face-to-face relation with their rims in juxtaposition, the rims being then sealed together along their periphery.

A plurality of filaments may be provided within the envelope, and, if desired, separate electrical connections may be made to each filament so that by energising one or more of the filaments the light output of the lamp may be varied. The electrical connections which support the filament or filaments within the envelope extend through the sealed joint between the two members to the exterior of the envelope, and by choosing for the conductor providing the connections to the filament a metal which has a temperature coefficient of expansion compatible with that of the vitreous material of which the members are formed, the risk of the seal breaking down when heated is reduced.

It is envisaged that the lamp will most often be mounted with the filament or filaments substantially horizontal by providing a suitable fitting which surrounds the envelope and to which the lamp is secured along at least part of its periphery. The fitting will be generally of electrically insulating material, but having contacts provided which engage with the electrical connections which extend through the joint between the members forming the envelope. Conventional electric incandescent lamps are usually operated with the support cap uppermost, and in this way the seal at the end of the glass bulb and the protective cap are at the hottest portion of the lamp; but an incandescent lamp in accordance with the present invention is conveniently secured to the fitting along at least part of its outer periphery and the seal between the two vitreous members can be arranged to be the coolest part of the lamp.

Each of the electrical connections to the filament which

2

extend to the exterior of the envelope may be terminated in a looped portion which serves as a terminal member by which the electrical supply is applied to the filament. The looped portion may follow the contour of the envelope in the vicinity of the seal through which the connection emerges from the envelope.

In an alternative embodiment of the invention, each of the electrical connections which extend to the exterior of the envelope is secured to one of a plurality of clips of conducting resilient material which are positioned on the flanged periphery of the envelope.

In order that the invention may be more readily understood, it will now be described with reference to the accompanying drawings, in which:

FIG. 1 is a perspective view of one embodiment of the invention,

FIG. 2 is a perspective view of a further embodiment of the invention, and

FIG. 3 is a perspective view of an alternative embodiment of the invention.

Reference numerals 1 and 2 denote pre-formed members of light transmitting vitreous material which are of generally rectangular configuration. The vitreous material may be, for example, a glass having suitable physical characteristics, fused silica, or a translucent sintered ceramic, and the members are formed by casting techniques or by distorting vitreous ribbon or sheet which has been raised to a temperature at which it is pliable. Each member is in the form of a trough having at its mouth an outwardly turned flat rim 3. To improve the operation or appearance of the lamp, the inner and outer surfaces of the members may be provided with a diffusing, fully reflecting, or selective reflecting coating. If it is desired to control the direction of light emission from the lamp, one or both of the pre-formed members may be made with prismatic or other flutes to refract light emitted into the desired directions. The surface of one or both of the members may be provided with a decorative design, if required.

40 The envelope is formed by positioning the two members together in face-to-face relation with their rims in contact and sealing them together along the periphery of the rims. At least one filament 4 is located within the envelope with the electrical connections thereto extending in sealed relation through opposed edges of the joint between the members to the exterior of the envelope. In the embodiment shown in FIG. 1, one filament is provided, and in the embodiments of FIGS. 2 and 3, four and three filaments, respectively, are employed.

45 The lamp is assembled by sandwiching one or more filaments and their connections between the adjacent rims of the two members and applying heat and pressure to the adjacent flanged surfaces of the members, thereby sealing the assembly. Exhausting and/or gas-filling of the envelope is carried out by means of a tube extending through an opening in the periphery of one of the members, the tube being subsequently sealed off.

50 In the embodiments of the invention shown in FIGS. 1 and 2, the electrical connections to the filaments or each filament extend in sealed relation through the joint and are terminated by contact strips 5 of resilient material which are located on the flanged periphery 3 of the envelope, and one of the electrical connections to the filament is connected to each strip. Two or more of the contact strips may be connected together so that the filaments are in series/parallel relation in order that one or more of the filaments may be energized as required.

55 FIG. 3 shows an embodiment of the invention in which a portion of each electrical connection to the filament which extends to the exterior of the envelope is terminated in a looped portion 6 which serves as a terminal

member by which the electrical supply may be applied to the filament. The looped portion may follow the contour of the envelope in the vicinity of the seal through which the connection emerges from the envelope.

When the filament of the lamp is of low power rating, the connections or each electrical connection which extends through the wall of the envelope is conveniently in the form of a thin wire which can easily be flattened into engagement with the wall of the envelope, so as to follow the contour thereof. If, however, the power rating of the filaments demands the electrical connections to be of thicker dimensions the resilience of the material from which the conductor is formed may make it impossible for the looped portion to be flattened completely into engagement with the wall of the envelope, in which case at least part of the looped portion will be spaced apart by a small distance from the wall of the envelope.

The end of the looped portion 6 of each connection is returned into the joint between the two pre-formed members on the same side of the envelope and is hermetically sealed therein. The two ends of the loop are thus rigidly secured in the joint between the two pre-formed members, and the loop serves as a terminal member. If desired, the loop extending between the two rigidly secured ends of the connection may be flattened down on to the wall of the envelope in the vicinity of the sealed ends of the connection to take up the contour of the wall. The single filament comprises three sections and the connections 4a between adjacent sections are sealed in the joint between the members.

What we claim is:

1. An electric incandescent lamp comprising a sealed light transmitting envelope composed of two trough shaped members with rims sealed together in opposed relation with the rims in contact, at least one filament within the envelope and electrical connections from respective ends of each filament extending in sealed relation between said rims to the exterior of the envelope with the end of each connection remote from the filament sealed between said rims to provide a looped terminal member for the filament.

2. An electric incandescent lamp comprising a sealed light transmitting envelope composed of two trough shaped members with outwardly flanged rims sealed together in opposed relation with the rims in contact, at least one

45 DAVID J. GALVIN, *Primary Examiner.*

filament within the envelope and electrical connections from respective ends of each filament extending in sealed relation between said flanged rims to the exterior of the envelope with the end of each connection remote from the filament sealed between said flanged rims to provide a loop terminal member for the filament.

3. An electric incandescent lamp comprising a sealed light transmitting envelope composed of two trough shaped members with outwardly flanged rims sealed together in opposed relation with the rims in contact, at least one filament within the envelope, and electrical connections from respective ends of each filament extending in sealed relation between said flanged rims to the exterior of the envelope with the end of each connection remote from the filament sealed between said flanged rims adjacent the other portion of the connection extending between said flanged rims to provide a looped terminal member for the filament.

4. An electric incandescent lamp comprising a sealed light transmitting envelope composed of two generally rectangular trough shaped members with rims sealed together in opposed relation with the rims in contact, at least one filament within the envelope arranged with its axis generally normal to the longitudinal axis of the envelope and electrical connections from respective ends of each filament extending in sealed relation between the rims along the longer sides of the envelope to the exterior thereof with the end of each connection remote from the filament sealed between said rims to provide a looped terminal member for the filament.

5. An electric incandescent lamp as claimed in claim 4, in which the rims are flanged and a single filament divided between its ends to form at least two sections is provided with the sections arranged normal to the longitudinal axis of the envelope and the connections between adjacent sections of the envelope located between said flanged rims.
